E. E. ELLIS

TILE MOUNTING DEVICE

Filed Aug. 21, 1924

Patented Apr. 14, 1925.

1,533,588

UNITED STATES PATENT OFFICE.

ELMER E. ELLIS, OF POMONA, CALIFORNIA.

TILE-MOUNTING DEVICE.

Application filed August 21, 1924. Serial No. 733,404.

To all whom it may concern:

Be it known that I, ELMER E. ELLIS, a citizen of the United States, residing at Pomona, in the county of Los Angeles and State of California, have invented certain new and useful Improvements in Tile-Mounting Devices; and I do declare the following to be a full, clear, and exact description of the invention, such as will enable others skilled in the art to which it appertains to make and use the same.

This invention is designed for holding floor or wall tiles in properly spaced relation while a piece of paper or other flexible sheet is being pasted on the upper side of the tile to hold the tile blocks in properly spaced positions, both while shipping, and when laying the tile floor. The usual manner of constructing tile-mounting boards is to take a wooden board of desired size, lay it off into areas having the same design as the blocks of tile to be mounted, and then insert thin strips of metal into the board to form partitions between the edges of the tile. This is very unsatisfactory, as the partitions become loose and drop out and furthermore, the wooden board will warp, shrink, expand, split and rot. It is the object of my invention however, to provide an improved form of tile mounting which consists of a metal support upon which to rest the blocks of tile, and flanges integral with and rising from said support for reception between the blocks of tile to hold the latter in properly spaced relation while applying the sheet of paper or the like thereto, the aforesaid flanges being preferably stamped upwardly from the metal support, which support may be formed of one piece or of a number of pieces of metal.

With the foregoing in view, the invention resides in the novel subject matter herein-after described and claimed, the description being supplemented by the accompanying drawings.

Figure 1 is a perspective view showing the metal support formed of a plurality of separate metal plates secured upon a base of any desired material, preferably a metal plate.

Figure 2 is a perspective view of one of the plates separated from the others.

Figure 3 is a vertical sectional view on line 3-3 of Fig. 1, showing the manner in which the blocks of tiling are held by the flanges.

Figure 4 is a perspective view of a construction in which all of the flanges are stamped upwardly from a single metal plate.

Figure 5 is a sectional view on line 5-5 of Fig. 4, showing only the flanges on the plane upon which the section is cut.

In the form of construction illustrated in Figs. 1, 2 and 3, the numeral 1 designates an appropriate, horizontal, flat base which is preferably in the form of a metal plate. Secured by rivets or the like 2, upon the upper side of the base 1, are individual plates 3 which are disposed in edge to edge relation, 70 said plates being angular or circular according to the shape of the tile blocks to be mounted, the plates in question being hexagonal in the present showing. Each plate 3 is provided with a plurality of upstanding flanges 4 at its periphery, and spaced apart about the latter, said flanges being integral with the plate and being preferably stamped upwardly therefrom. The plates are so related that the flanges of each plate are disposed in the spaces between the flanges of adjacent plates. For instance, when the plates are hexagonal, each plate will be provided with three flanges and with three edges having no flanges, and when securing the plates upon the base 1, they are positioned so that the flanged edges of said plates abut the flangeless edges of adjacent plates.

In the form of construction illustrated in Figs. 4 and 5, a single metal plate 3^a has flanges 4^a which are upwardly stamped at the desired locations. In either form of construction, the flanges surround the individual tile blocks and correctly space the latter apart, so that when a sheet of paper or the like is pasted or otherwise secured upon them, they will be held in properly spaced relation. After the pasting operation, a suitable board or the like is laid upon the paper and the entire device is inverted with this board, the tiling and the paper. Thus, the tile mounting device may be removed from the tile, leaving the latter pasted in orderly fashion upon the sheet, for shipment and for proper laying in cement.

Attention is directed to the fact that each of the flanges 4 or 4^a has its ends spaced from adjacent ends of other flanges. This permits easy access to a corner or corners of each tile until obstructed by laying of another tile or tiles. Thus, if the artisan work-

- ing out a design upon the board, should place a tile of the wrong color in one of the pockets formed by the flanges, he has access to a corner or corners of such tile, so that it can be readily engaged with the fingers and removed, or possibly a thin instrument could be inserted in the gap between two of the flanges and forced between the tile and the metallic base to lift the former.
- 10 As excellent results may be obtained from the details disclosed, they are preferably followed, but within the scope of the invention as claimed, minor changes may of course be made and obviously the device in any of its forms may be of any desired dimensions.

I claim:

1. A device for holding tiling while applying a sheet thereto, comprising a flat horizontal metal support upon which to rest a plurality of blocks of tile, and flanges integral with and rising from said support for reception between the blocks of tile to hold

the latter in properly spaced relation, each flange having its ends spaced from adjacent ends of other flanges, permitting easy access 25 to a corner or corners of each tile until obstructed by laying of another tile or tiles.

2. A device for holding tiling while applying a sheet thereto, comprising a base, and a plurality of metal plates secured thereon in 30 edge to edge relation, each plate having up-standing integral flanges spaced apart around its periphery, each plate having its flanges disposed in the spaces between flanges of adjacent plates.

3. A structure as specified in claim 1, said flanges being upwardly stamped from the metal support.

4. A structure as specified in claim 2; said flanges being upwardly bent from the edges 40 of said plates.

In testimony whereof I have hereunto affixed my signature.

ELMER E. ELLIS.
